UNITED STATES PATENT OFFICE.

WILLIAM RICHARD LOGAN, OF LOS ANGELES, CALIFORNIA, ASSIGNOR OF ONE-HALF
TO AUGUST BEHRSIN, OF LOS ANGELES, CALIFORNIA.

FURNACE-BURNER FOR LIQUID FUEL.

1,248,875.

Specification of Letters Patent. Patented Dec. 4, 1917.

Application filed October 4, 1916. Serial No. 123,681.

To all whom it may concern:

Be it known that I, WILLIAM RICHARD LOGAN, a citizen of the United States, residing at Los Angeles, in the county of Los Angeles and State of California, have invented a new and useful Furnace-Burner for Liquid Fuel, of which the following is a specification.

My invention relates to improvements in a furnace burner for liquid fuel in which the mixture of the fuel and the fluid by which it is atomized is effected outside of the device, and the objects of my invention are to provide a burner of simple form that is easily cleaned and one in which the width and height of the discharge ports for both the oil and the steam, or other vehicle, is easily and quickly adjusted in the same burner to meet the widely varying conditions of practice and to afford means within the burner for pointing the flame in any desired direction to suit the requirements of the furnace.

I attain these objects in the mechanism illustrated in the accompanying drawings in which—

Figure 1 is a side elevation in section of the entire device. Fig. 2, is a front view of the entire device. Fig. 3, is an inside view of one of the halves forming the body of the device. Fig. 4, is a top view of one of the plates 5 or 7 which shows the cut for the discharge port and shows the diaphragm 6 behind.

Similar figures refer to similar parts throughout the several views.

The body of the device is composed of the two like halves 1 and 2 carrying the annular channels 3 and 4, respectively, which communicate, respectively, by the ports 9 and 10 with the oil and the steam conduits 11 and 12.

Between these two halves 1 and 2 is firmly held by the center bolt 8 the oil plate 5, the diaphragm 6 and the steam plate 7.

In the operation of the device steam, or other like fluid, in proper amount, is admitted to the burner by the conduit 12. The steam then enters the channel 4 and passes out from the burner, like the spread of a fan, by the cut 14 in the plate 7. Oil, in proper amount, is then admitted by the conduit 11

to the burner. The oil then enters the channel 3 and passes out by the cut 13 in the plate 5 and falling upon the spread of out-flowing steam, issuing from the cut 14, is carried away in a properly atomized state for burning.

The steam plate 7 is of such a thickness in comparison with the oil plate 5 as to properly proportion, within certain limits, the amount of steam to the amount of oil issuing from the burner.

If a heavy or a light fire is required thick or thin plates for the steam and the oil with a proper width of cut to accommodate the burner to the width of the furnace, are placed between the two halves of the burner body, all being firmly held together by tightening the center bolt 8.

The direction of the flame from the burner can easily be changed by loosening the bolt 8 and turning the oil and steam plates together with their separating diaphragm 6 to any point in a complete circle.

It is obvious that, with the oil meeting the atomizing fluid outside of the burner, oil under a very low pressure can be used; the burner being easily adapted to such a wide difference between the oil and steam pressures by inserting into the burner an oil plate considerably thicker than the steam plate.

Having thus described my invention I claim—

1. In a liquid fuel burner, a casing comprising two members, a hole through the center of each member, a disk between said members, a plate between said disk and one of the members and having a fan-shaped cut from its periphery, another plate between said disk and the other member and having a similar portion but larger cut away from its periphery, means for securing said disk and said plates together, comprising holes through said disk and plates adapted to register with the holes in the members; a bolt in said holes, and means to secure said bolt and to hold the members and the disk and plates together or to allow said disk and plates to be turned in any degree of the circumference of the members.

2. In a liquid fuel burner, the combination with two members of a casing adapted

to be clamped together, of a central disk between said members, a plate on either side of said disk and having portions cut from their peripheries one larger than the other, 5 and means to clasp the two members and the disk and plates rigidly together or to allow the disk and plates to be turned so that the

outer portions of the plates may be made to face in any direction.

WILLIAM RICHARD LOGAN.
